UNITED STATES PATENT OFFICE.

ALFRED BRUNO SEPPMANN, OF LAKE CRYSTAL, MINNESOTA.

VALVE-SPRING COMPRESSOR.

Application filed May 5, 1921. Serial No. 467,165.

To all whom it may concern:

Be it known that I, ALFRED BRUNO SEPPMANN, a citizen of the United States, residing at Lake Crystal, in the county of 5 Blue Earth, State of Minnesota, have invented a new and useful Valve-Spring Compressor; and I do hereby declare the following to be a full, clear, and exact description of the invention, such as will enable others 10 skilled in the art to which it appertains to make and use the same.

The invention relates to valve spring compressors and has for its object to provide a device of this character which is disposed 15 on a bench and so constructed that a cylinder head may be disposed adjacent the same, and the valve springs carried thereby easily compressed, thereby allowing the cotter pin and valve stem to be easily removed and the 20 valve disassembled.

A further object is to provide a valve spring compressor for benches, which compressor comprises a horizontally disposed rod carried by the bench on which rod is longitudinally movable a clevis which may swing vertically, said clevis having pivoted thereto a yoke which may swing in a horizontal plane; thereby in connection with the clevis forming a traveler having a universal 25 movement, slidably mounted in the yoke and operating lever which operating lever is provided with a downwardly extending valve stem washer engaging arm, which may be positioned in various positions for forcing 30 downwardly a washer of the valve stem and compressing the valve spring.

A further object is to provide means whereby the valve spring compressor may be utilized for stretching the spring, there- 40 by restoring the tension necessary in the spring.

With the above and other objects in view the invention resides in the combination and arrangement of parts as hereinafter set 45 forth, shown in the drawings, described and claimed, it being understood that changes in the precise embodiment of the invention may be made within the scope of what is claimed without departing from the spirit of the 50 invention.

In the drawings:—

Figure 1 is a front elevation of the valve spring compressor.

Figure 2 is a top plan view.

Figure 3 is a detail perspective view showing the device used as a valve spring stretcher.

Referring to the drawings, the numeral 1 designates a portion of a work bench and 2 a cylinder head of the type wherein the 5 valves are carried by the cylinder head. Extending upwardly from the bench 1 and secured thereto is a U-shaped bracket 3, which bracket supports and forms a traveler for the valve stem compressor hereinafter set 65 forth.

Slidably mounted on the horizontal portion 3^a of the U-shaped bracket 3 is a clevis 4, which clevis pivots in a vertical plane as well as moves longitudinally on the portion 70 3^a of the bracket 3. Pivotedly connected at 5 to the clevis 4 and adapted to swing in a horizontal plane is a guide yoke 6, in which yoke is slidably mounted the end 7 of an operating lever 8. It will be seen that the 75 operating lever is universally supported to any position desired for positioning the downwardly extending arm 9, which is secured to the operating lever by means of a bolt 10 over any particular valve of the cylinder head 2 without removing the cylinder head from its position on the bench 1, or moving the cylinder head 2 to a particular position for positioning the valve stem 11, which would be necessary if the operating 80 85 lever 8 were not slidably mounted in a member which has a longitudinal movement and a universal movement.

The lower end of the downwardly extending arm 9 terminates in a horizontally disposed bifurcated member 12, the arms of which portion are adapted to be disposed on the upper surface of the washer 13 in such a manner that when said washer is forced downwardly for compressing the valve 95 spring 14, the cotter key 15 will pass upwardly through the bifurcation to a point where it can be easily and quickly removed with any suitable tool. It will be seen that the valve springs may be quickly compressed 100 and the valve disassembled and the danger of bending the valve stem 11 which is common where the valve is disassembled by ordinary tools.

After the valve spring 14 has been removed and it is found necessary to stretch the spring for restoring its normal tension, the device may be utilized for this purpose.

To accomplish the stretching operation the U-shaped spring holder 15^a is removed from the downwardly extending bracket 16 and is placed through the aperture 17 in the operating lever 8 with its hooked arm extending downwardly. The arms 18 of the U-shaped member 15 are then forced into the end of the coiled spring 4 until their hooks 19 engage over and receive the upper convolution of the spring. After the upper end of the spring has been secured, the lower end of the spring is similarly connected to a similarly shaped U-shaped spring clamp 20, carried by the bracket 16. Spring holding member 15^a and 20 being of the same construction the same numerals apply thereto. After the spring 14 is so positioned and held, it will be seen that upon an upward movement of the lever 8 that the spring will be 20 stretched in such a manner that its tension may be restored.

From the above it will be seen that a valve spring compressor is provided, which compressor is particularly adapted for use in connection with benches whereon the entire cylinder head of an internal combustion engine is disposed for repairing and overhauling or assembling the valve carried by said cylinder head. It will also be seen that it will not be necessary to accurately dispose the cylinder head in relation to the device, it being only necessary to place the cylinder head adjacent the device and after which any

of the valve stems may be quickly reached by the horizontal portion 12 of the arm 9. 35 The invention having been set forth what is claimed as new and useful is:—

1. A valve spring compressor comprising a supporting bracket, said bracket having slidably and rockably mounted thereon a 40 clevis, a yoke horizontally pivoted on said clevis, an operating lever slidably mounted in said yoke and a downwardly extending valve spring engaging arm carried by said lever.

2. A valve spring compressor comprising a supporting bracket, a slideable member slidably mounted on said bracket and rockably mounted thereon, a yoke carried by said slideable and rockable member and horizontally pivoted to said member, an operating lever slidably mounted in said yoke, a downwardly extending arm carried by said operating lever and a valve stem washer engaging member carried by said downwardly extending arm and adapted to engage a washer for forcing the same downwardly and compressing a valve spring. 55

In testimony whereof I have signed my name to this specification in the presence of 60 two subscribing witnesses.

ALFRED BRUNO SEPPMANN.
